SEPARATING TABLES

Ian D. Russell, Sandringham, Johannesburg, Union of South Africa, assignor to The Denver Machinery Company (Proprietary) Limited, Johannesburg, Transvaal, Union of South Africa

Filed Oct. 29, 1958, Ser. No. 770,559

6 Claims. (Cl. 209—458)

This invention relates to the separation of substances into two fractions, one of which is heavier than the other, by making use in the main of a difference or differences in specific gravities.

In particular it relates to the separation of the mineral content from the waste content of ores which have been reduced to fluid-solid mixtures, in which the degree of fineness of the solids and the proportion by weight are suited to the particular ore involved.

Known separating tables employ the principle that, in a metallurgical fluid-solids mixture moving over a surface, the heavy fraction or fractions tend to settle on the surface while the lighter fraction or fractions remain in the top layer and are carried over the surface. An example of a separating table is that employed in the gold mining industry, comprising a table of corduroy, over which the gold-bearing fluid-solids mixture is run transversely to the corrugations of the material. The gold settles against the riffles and is removed by known methods.

It is an object of the present invention to provide a separating table that permits a continuous separation of mineral or minerals at a greater rate than was previously attainable and with a greater efficiency.

According to the invention a separating table for metallurgical fluid-solids mixtures or the like comprises two or more surfaces ribbed longitudinally to form channels, the walls of which are the ribs, the ends of adjacent surfaces being separated by transverse gaps, adjustable blade means associated with and overhanging the gaps and adapted to contact with its leading edge the ribs near the trailing edge of the surface with respect to the direction of the flow of the fluid-solids mixture to present a series of adjustable openings to the flow of the mixture.

In the preferred form of the invention, the separating table may comprise a cascade of ribbed surfaces along the length of the table.

The functions of the channels are at least threefold. Firstly the heavy fraction or fractions are assisted thereby to gravitate towards the bases of the channels and so to separate from the lighter fractions. Secondly, they prevent the fluid-solids mixture, when fed under proper conditions, from flowing to one or other side after entering the channels, should the table not be perfectly level across its width. Thirdly, the channels assist to distribute the flow satisfactorily over the full width of the table, and thereby ensure as far as possible even gravitation of the heavy fraction or fractions. The blade means is preferably mounted at or near the leading edge of a surface with respect to the direction of flow of the fluid-solids mixture and overhangs the gap to a variable partial extent. The leading edge of the blade with respect to the direction of flow of the fluid-solids mixture, which edge is hereinafter referred to as the leading edge of the blade, comes into contact with the ends of the walls of the channels near the trailing edge of a preceding surface with respect to the direction of the flow of the fluid-solids mixture, the latter edge being hereinafter referred to as the trailing edge of the preceding surface.

2

The ends of the walls of the channels or the ends of the extensions of such walls are hereinafter referred to as the ends of the ribs. Thus, the heavier fraction or fractions pass through the adjustable openings formed by the bases of the channels, the ends of the ribs and the leading edge of the blade. The lighter fraction or fractions flow over the blade means to the next surface where further gravitation of the fraction or fractions will take place.

The method of mounting the blade must be such that it can be moved in planes normal and planes parallel to the surface of the table, and can also be tilted, since for proper operation of the table the leading edge of the blade must always be in contact with the ends of the ribs.

In a modified form of the invention the blade is mounted at or near the leading edge of a surface with respect to the directions of flow of the fluid-solids mixture in a similar way to the preferred form, and is in contact with the bottom of those parts of the ribs which overhang the trailing edge of the preceding surface, and overhangs the gap to a variable partial extent. As in the case of the preferred form, the heavier fraction or fractions pass through the adjustable openings which in the modified form are thus formed by the leading edge of the blade, the bases of the channels at the trailing edge of the preceding surface and parts of the ribs. The adjustable openings may also be formed by adjusting the blade back in the direction of flow of the fluid-solids mixture, and then adjusting it to come in contact with the ends of the ribs. The method of mounting the blade must be such that it can be moved in planes normal and planes parallel to the surface of the table, and can also be tilted.

In the majority of cases turbulence is undesirable for a successful separation, and the underside of the blade is designed in such a manner as to maintain as streamlined a flow as possible after the heavy fraction or fractions have passed through the adjustable openings. The trailing edge of the preceding surface and the ends of the ribs may also be designed to maintain as streamlined a flow as possible. In the three cases the designs contemplated are curvatures sufficient to create a streamlined flow. The width of the ribs may also be designed in such a manner as to obviate turbulence as much as possible.

In the operation of the table, a fluid-solids mixture containing the mineral or minerals is fed on to one end substantially evenly, the table being approximately level across its width and the longitudinal slope and degree of cascading being determined by experiment for different ores.

The heavy fraction or fractions having gravitated towards the bases of the channels pass through the adjustable openings to a collecting tray while the lighter fraction or fractions pass over the blade to the following ribbed surface.

The table may either be stationary or may be vibrated during the operation.

According to the substance or substances to be separated, it may be necessary to include one or more flotation reagents, wetting agents or other compounds to assist in the separation of the heavy fraction or fractions from the light fraction or fractions. For example, it may be that due to the particle sizes of the heavier fraction or fractions coupled with the surface tension effect, the heavy particles are caused to float on the surface of the fluid-solids mixture. The addition, for example, of a wetting agent may remove this difficulty.

An embodiment of the invention is described hereunder with reference to the accompanying drawings in which

Figure 1 is a perspective view of a separating table;

Figure 2 is a sectional side or longitudinal view of a portion of the table in a preferred form illustrating a gap and an adjustable plate;

Figure 3 is a transverse section on the line 3—3 of Figure 1, and

Figure 4 is an enlarged sectional side or longitudinal view of a portion of the table in a modified form illustrating a gap and an adjustable blade.

The table is bound by walls 10 and 11 and comprises a cascade of units, in this case, four, each of which consists of a flat base 12 upon which are located longitudinal ribs 13. Thus channels are formed by flat bases 12 and the ribs 13.

At the end of each unit there is a gap 14, leading to a drawing-off means, in this case represented by a gutter 15, along which the separated portion may flow to collecting means. The bases 12 of the table terminate in a curved portion 16, the curvature of which is designed to minimise turbulence at that point, since any turbulence would cause mixing of the heavy and lighter fractions. The ribs 13 terminate at the gaps, and the ends of the ribs are at an angle of approximately 135°, with a plane parallel to the surfaces of the units.

Referring to Figure 2, a blade 17 pivoted at 18 is provided along its length with a number of adjusting screws 19 by which the angle of the blade in relation to the table, its height above the table and its longitudinal position on the table may be varied, and consequently the adjustable openings formed by the bases of the channels, the ends of the ribs 22 and the leading edge of the blade when in contact with the ends of the ribs may be varied for different metallurgical fluid-solids mixtures. Adjustment of the blade in any of the directions of adjustment must be done in such a manner that on completion of the adjustment the leading edge of the blade is in contact with the ends of the ribs 13.

The leading edge of the blade touches the ends of the ribs 13 at points 20 so that the heavy fraction or fractions pass through the adjustable openings, while the lighter fraction or fractions pass over the top of the blade to the following unit of the table, where the operation is repeated until the remainder of the fluid-solids mixture passes over the trailing end of the table with respect to the direction of flow of the fluid-solids mixture.

In order further to promote tranquility of flow in the neighbourhood of the blade, the under side of the blade may be curved at 21 along the length of the blade, the radius of curvature being suitably chosen with a view to minimising turbulence. For the same reason the ends of ribs may be rounded, the radius of curvature being suitably chosen with a view to minimising turbulence.

Referring to Figure 4, a blade 17 pivoted at 18 is provided along its length with a number of adjusting screws 19. The head 23 of a screw 19 is located within a depression 24 of the blade 17. By tightening or loosening the screw 19, the blade may be adjusted in a plane substantially normal to the table. It will also be seen that the screw 19 is able to slide within the hole 25 so that the blade 17 is adjustable in a plane parallel to the table. Since the blade 17 is pivoted at 18, relieving the tension on bolt 19 by turning the nut towards the free end thereof, will cause the edge 20 to be lowered because of the disposition of the gutter 15 relative to the pivot 18. Obviously, when the nut is tightened on the bolt 19, the edge 20 is moved upwardly.

In operation the fluid-solids mixture to be concentrated is passed on to the table substantially evenly, the table being approximately level across its width, in the direction shown in Figure 1 by the arrows A. Each blade is set to a predetermined angle, height and longitudinal position according to the composition of the fluid-solids mixture and other factor which may be relevant. The table is sloped to a predetermined degree according to the rate at which the fluid-solids mixture is to pass over the table.

For satisfactory working the bases of the channels must be flat and the sides of the ribs should be inclined slightly.

For concentrating certain fluid-solids mixture the bases of the channels should be of the order of one-eighth of an inch wide.

As the fluid-solids mixture flows along the channels, the difference in specific gravity causes the heavy fraction or fractions to gravitate towards the bottoms of the channels.

The separating results have been found to be much more satisfactory where instead of a gap between the leading edge of the blade and the trailing edge of the preceding surface a number of adjustable openings are provided for as described foregoing.

At the trailing end of a surface a certain proportion of the heavy fraction or fractions is present in the lower sections of the channels. By having adjustable openings instead of a gap at the end of the preceding surface, and by making provision for maintaining as streamlined a flow as possible through the adjustable openings in the manner indicated foregoing, such proportion of the heavy fraction or fractions is maintained as much as possible, thus ensuring that as much of such fraction or fractions as possible flow through the adjustable openings.

Having collected the different fractions at the points 15 the fractions are either re-introduced on to the table or another table or further treated in some other way.

In constructing a table according to the invention, care should be taken to ensure that the ribs are as thin as possible and at the required distance apart having regard to the ore mixture to be treated. The sides of the ribs should be sloped, the angle again depending on the mixture of ores to be separated since the sides of the ribs assist materially in the separation and prevent blocking of the openings by large particles. Particles which have the same or greater diameter as the width of the channels and of the openings, will tend to ride above the blade.

I claim:

1. A separating table for metallurgical fluid-solids mixtures comprising at least two surfaces longitudinally ribbed, the ends of adjacent surfaces being separated by transverse gaps, at each gap blade means mounted at the leading edge of each surface with respect to the direction of flow of the fluid-solids mixture, means to adjust the blade means substantially parallel to the surface of the table, means to adjust the blade means in a plane substantially normal to the surface of the table and means to tilt the blade means, the blade means overhanging the gap and contacting the ribs at the trailing edge of a surface with respect to the direction of flow of the fluid-solids mixture to present a series of adjustable openings to the flow of the mixture.

2. The separating table as claimed in claim 1 in which the ribs overhang the gaps to an extent whereby the ends of the ribs form, in longitudinal section an angle of about 135° with a plane parallel to the surface of the table.

3. The separating table as claimed in claim 1 in which the trailing edge of each surface is shaped to promote tranquil flow of the heavy fractions of the fluid-solids mixture thereover.

4. A separating table for metallurgical fluid-solids mixtures comprising at least two surfaces longitudinally ribbed, the ends of adjacent surfaces being separated by transverse gaps, at each gap blade means mounted at the leading edge of each surface with respect to the direction of flow of the fluid-solids mixture, means to adjust the blade means substantially parallel to the surface of the table, means to adjust the blade means in a plane substantially normal to the surface of the table and means to tilt the blade means, the blade means overhanging the gap and contacting the ribs at the trailing edge of a surface with respect to the direction of flow of the fluid-solids mixture to present a series of adjustable openings to the flow of the fluid-solids mixture, the trailing edge of each surface being shaped to promote tranquil flow of the heavy fractions of the fluid-solids mixture thereover, and the ribs overhanging the gaps to an extent whereby,

the ends of the ribs form, in longitudinal section an angle of about 135° with a plane parallel to the surface of the table.

5. A separating table for metallurgical fluid-solids mixtures comprising at least two surfaces longitudinally ribbed, the ends of adjacent surfaces being separated by transverse gaps, at each gap blade means mounted at the leading edge of each surface with respect to the direction of flow of the fluid-solids mixture, means to adjust the blade means substantially parallel to the surface of the table, means to adjust the blade means in a plane substantially normal to the surface of the table and means to tilt the blade means, the blade means overhanging the gap and contacting the ribs at the trailing edge of a surface with respect to the direction of flow of the fluid-solids mixture to present a series of adjustable openings to the flow of the fluid-solids mixture, the trailing edge

10

of each surface being shaped to promote tranquil flow of the heavy fractions of the fluid-solids mixture there-over and the underside of the blade means being shaped to promote tranquil flow of the fluid-solids mixture there-under.

6. The separating table as claimed in claim 5 in which the ribs overhang the gaps to an extent whereby the ends of the ribs form, in longitudinal section an angle of about 135° with a plane parallel to the surface of the table.
